UNITED STATES PATENT OFFICE.

OLE HERMANSON, OF SUN PRAIRIE, WISCONSIN.

DESIGN FOR A STAPLE-PULLER.

58,569.

Specification for Design.

Patented Aug. 2, 1921.

Application filed October 28, 1920. Serial No. 420,300. Term of patent 7 years.

To all whom it may concern:

Be it known that I, OLE HERMANSON, a citizen of the United States, residing at Sun Prairie, in the county of Dane and State of Wisconsin, have invented a new, original, and ornamental Design for Staple-Pullers, of which the following is a specification, reference being had to the accompanying drawing, forming part thereof.

Figure 1 is a side elevational view showing my new design, and

Fig. 2 is a sectional view taken on the line 2—2 of Fig. 1.

I claim:

The ornamental design for a staple puller, as shown.

In testimony that I claim the foregoing I have hereunto set my hand at Sun Prairie, in the county of Dane and State of Wisconsin.

OLE HERMANSON.
